UNITED STATES PATENT OFFICE

GUSTAVE M. MINTON, OF NEW YORK, N. Y.

DESIGN FOR A TELEPHONE STAND

Application filed October 30, 1930. Serial No. 37,461. Term of patent 7 years.

To all whom it may concern:

Be it known that I, GUSTAVE M. MINTON, a citizen of the United States of America, residing in New York, county and State of New York, have invented a new, original, and ornamental Design for a Telephone Stand, of which the following is a specification, reference being had to the accompanying drawings, forming part thereof, in which—

Fig. 1 is a perspective view of the design, and

Fig. 2 is a plan view thereof.

I claim:

The ornamental design for a telephone stand as shown.

GUSTAVE M. MINTON.
